ATTORNEY

UNITED STATES PATENT OFFICE

RITA BERMAN, OF NEW YORK, N. Y.

DESIGN FOR A NURSERY TOY

Application filed January 10, 1931. Serial No. 38,268. Term of patent 7 years.

To all whom it may concern:

Be it known that I, RITA BERMAN, a citizen of the United States, residing at New York, county and State of New York, have invented a new, original, and ornamental Design for Nursery Toy, of which the following is a specification, reference being had to the accompanying drawing, forming part thereof.

The figure is a perspective view of a nursery toy showing my new design.

I claim:

The ornamental design for a nursery toy, as shown.

RITA BERMAN.
